SINGLE SHEET DELIVERY DEVICE FOR WEB FED PRESS

Laszlo M. Stempel, Metuchen, N. J., assignor to John Waldron Corporation, New Brunswick, N. J., a corporation of New Jersey

Application June 24, 1954, Serial No. 439,121

6 Claims. (Cl. 198—31)

This invention relates to printing presses and more particularly to high speed web fed presses which cut the printed web into sheets and stack them.

It is a general object of the present invention to provide a novel and improved printing press of the type defined.

More particularly it is an object of the invention to provide in a printing press of the character described mechanism for delivering to a separate point, a single sheet from a position immediately following the cutter without disrupting the stacking operation.

An important object of the invention relates to the use of mechanism which upon manual initiation automatically opens a sheet diverter at the appropriate time, closes it and resets and locks the mechanism ready for further use.

Another object of the invention comprises the arrangement of a second pull roll assembly for acting on the leading end of the web prior to cutting in a manner identical to that of the main pull roll assembly, both being driven at a higher peripheral speed than the roll delivering the web to the cutter but provided with less nip.

Another important object of the invention consists in the arrangement of a diverter trap door in the web supporting plate extending between the cutter and the main pull roll adapted, when open, to deflect the advancing uncut web end to a lower level and into the nip of a secondary pull roll.

Here an important feature resides in mechanism for closing the diverter trap door before the trailing end of the freshly cut sheet passes through its controlled opening, which latter is larger than the door, to ready the web supporting plate for the rapidly following lead edge of the web.

Still another important feature of the invention resides in the provision of manual means for disabling the single sheet delivery feature of the device to adjust it for continuous delivery ahead of the sheet stacker.

Among the other important features of the invention may be listed:

Mechanism for insuring uniform sheet length.

Single stroke, resetting mechanism for diverting a single sheet subject to the same uniform sizing feature.

The use of independent springs, one for raising the diverter trap door and the other to maintain the cam follower against the cam when the first is immobilized.

Other and further objects and features of the invention will be more apparent to those skilled in the art upon a consideration of the accompanying drawings and following specification, wherein is disclosed a single exemplary embodiment of the invention, with the understanding that such changes and modifications may be made therein as fall within the scope of the appended claims without departing from the spirit of the invention.

In said drawings:

Fig. 1 is an elevation of the single sheet delivery de-

2

vice looking from the discharge end of a web fed printing press;

Fig. 2 is a longitudinal, vertical section of the sheet severing and single sheet delivery portion of a web fed printing press taken on the plane of line 2—2 of Fig. 1 looking in the direction of the arrows;

Fig. 3 is a fragmentary, longitudinal vertical section taken on the plane of line 3—3 of Fig. 1 looking in the direction of the arrows and showing the trap door operating cam and cam follower;

Fig. 4 is a top plan view of the manual initiating lever, the lever and trap door actuating spring and the cam driven cross-shaft; and

Fig. 5 is a fragmentary side elevation of the manual lever shown in solid lines in the locked or non-delivery position and in dotted lines at the position of maximum automatic displacement.

In the operation of high speed, web-fed, rotary printing presses of either the offset or intaglio impression type, it is often the practice to incorporate in or following the mechanism of the press, means for severing the printed web into sheets at appropriate positions coordinated with and between the printing impressions thereon, and to stack the cut sheets. As the speeds of the presses have been increased to the almost incredible one of 25,000 sheets per hour in multi-color and on one or both sides of the web, several problems have arisen in connection with the cutting and stacking of the sheets, and the present invention is directed to the solutions thereof. Perhaps the main trouble results from the use of relatively thin papers which are hard to maintain flat while advancing, cutting and delivering because of their tendency to float or glide in the air, curl on the edges, bend up or down at the corners and otherwise flutter and deviate from their desired courses.

In the copending application of Pomper and Waechter, Serial. No. 365,376, filed July 1, 1953, now Patent 2,769,495, granted November 6, 1956, is disclosed apparatus for cutting the printed web, delivering and stacking the sheets, and the present invention may be used with such apparatus or with other satisfactory cutting and stacking devices. It deals primarily with the taking of single sample sheets from the press following the cutting operation and without disturbing the delivering and stacking mechanism. As an ancillary feature means are provided to insure uniform length of the sheets by applying a definite predetermined tension to the web for the cutting operation. This same tension is applied whether the sheets are advancing to the stack or being delivered for test samples by the single sheet delivery mechanism.

The apparatus shown in the several figures of the drawing relates only to the mechanism near the cutting and delivery end of the printing press, and there is shown at W a reach of the web rising substantially vertically and in its finished condition as regards printing, perforating, slitting or the like and ready for transverse cutting and stacking. This web passes over the first feed or pull roll 10 for horizontal delivery therefrom and hence has approximately a 90° contact therewith to insure a uniform rate of pulling without slippage, the contact being augmented by the pull wheels or idlers 11, preferably rubber tired and bearing at least near the edges of the web. They may be spring pressed to insure adequate engagement pressure.

The leading edge of the web W' advances over the two spaced parts 12 and 13 of the web supporting plate, which is substantially horizontal, as shown, and beneath the knife cylinder 15. In so doing the web passes over the cutting edge of the ledger plate or stationary knife blade 16, mounted between the parts of the supporting plate, and which cooperates with the movable blade 17 mounted in the cutting cylinder 15. This cylinder is timed to

rotate in proper respect to the pull roll 10 and the printing on the web, to cut off the desired length of sheet, all as disclosed in the above noted application. The length of sheet to be cut is in every case more than the distance between the edge of the ledger plate and the nip of the second pull roll 18 positioned behind the cutting position. Thus the web is tightly held between the nip of feed roll 10 and that of pull roll 18. This latter roll is of steel and driven at a peripheral speed of the order of 20% higher than that of pull roll 10. The nip, however, or contact is of the minimum and the tension of the idler wheels 19 is not high. Under these circumstances when the leading edge of the web reaches roll 18 it is put under a uniform tension and maintained thus as long as it is intact between the two rolls, slippage occurring at 18 only because of its lesser nip.

When the web is cut between blades 16 and 17 the leading edge of the remaining portion is advanced at its standard rate by feed roll 10 while the trailing edge of the cut sheet moves away from it under the superior speed of roll 18, carrying the cut sheet above the stack 20 on the pile board, where it is caused to be piled up, preferably in the manner defined in the earlier identified application. The use of a large nip feed roll and a more rapidly advancing second pull roll of less nip insures extreme accuracy in length of the sheets successively cut from the web since the tension of the web at the time of cutting is always the same.

In many cases it is highly desirable to be able to extract a single sheet for inspection of the quality of the work being currently done by the press, but because of the arrangement of the stacking mechanism many parts are in the way, and to reach in and grab a sheet moving at such high speed would be not only difficult but even dangerous, and certainly disrupting to the operation of the stacking mechanism, so means is provided permitting the operator to obtain a single sheet or a plurality delivered ahead of the stacking mechanism without interrupting its operation or changing the length of the cut sheet.

For the purpose of this feature of the invention the web supporting plate 13 is provided with a diverting trap door 22 having a flat top surface 23 substantially coincident with the top surface of plate 13 in its normal or closed position. However, upon initiation of a sampling operation, which will later be described, the forward edge of the trap door is lifted, as the advancing edge of the web approaches, and a diverter guide plate 24 on the under side thereof directs this edge of the web downwardly into the nip of secondary pull roll 26 and its cooperating idler wheels 27. Roll 26 has the same peripheral speed as roll 18, plus less nip than roll 10, so that it acts exactly as roll 18 in maintaining the same uniform tension on the web prior to and during cutting. It also carries the sample sheet away more rapidly than the advancing edge of the web from which it has just been cut. As the sheet leaves the downwardly inclined nip of rolls 26 and 27 it is deposited in an appropriate container or the like occupying space just forward of the pile board and the rear guides 28 for the cut sheets from which it is readily removable manually.

Referring now to Fig. 1, an elevational view of the important elements of the invention dealing with the trap door and associated mechanism, the machine will be seen to be assembled between proper side frames 30 and 31 of any desired construction, forming continuations of the side frames of the printing mechanism. In them are journaled all of the rolls, cylinders, shafts and the like illustrated in the present invention, but most of them, including all of the paper handling rolls and the cutting cylinder, have been omitted from this figure for the sake of clarity. Longitudinally adjustably secured in each side frame is stud 32 having an enlarged end housing non-friction bearing 33, the inner race of which receives the trun-

nion 34 which with its companion form the pivot for the trap door assembly 22.

These trunnions extend from lugs 35 secured to the top plate 23 of the trap door and to the side flanges 36 which reinforce and stiffen the same. Conveniently the forward portion of top plate 23 is bent and directed backwardly and downwardly to form the web diverter portion 24 which may be continuous or in the form of strips, as desired, for the sake of lightness since the trap door must be moved at high speed. The trunnions 34 are positioned above the level of the plate 23 and mounted at such a height as to hold this level substantially in alignment with the web supporting plate 13. These fulcrum studs 34 are closely adjacent the nip between pull roll 18 and its rubber tired wheels 19, as seen in Fig. 2, while the leading edge 37 of the trap door is slightly spaced from the rear edge of plate 13, as seen at 38. This is so the trap door can be closed before the trailing edge of the sheet in the nip of roll 26 and wheel 27 is completely clear of the trap door opening. By this means the door can be closed promptly, ready to guide the advancing end of the web to the stacking mechanism after a single sheet has been removed from beneath the trap door. The diverter 24 is properly angled to permit this operation.

As seen in Figs. 1 and 2, the trap door is adapted to be lifted by a pair of lift links 40, one at either side, connected by appropriate bearings and studs to lugs 40' secured to the side flanges 36 of the trap door assembly about midway of its length in the direction of web travel.

The upper ends of the lift links 40 are respectively pivoted to the ends of levers 41 and 42 on opposite sides of the machine. The hubs 41' and 42' of levers 41 and 42 are secured to rock shaft 43 by the pins shown, and this shaft is journaled in the side frames for rocking motion, which it will be appreciated lifts and then closes the trap door in a manner which will be obvious from Fig. 2, the dotted line position showing the maximum opening of the trap door and the full line position showing its closed position for permitting delivery of sheets to the stacker.

The two levers 41 and 42 move in unison with the rock shaft 43 and are biased upwardly by means of the substantially vertical spring VS the upper end of which bears against a flat surface and surrounds stud 44 on lever 41 near its pivot to link 40, while the lower end of the spring surrounds stud 45 and bears on the head 46 of its carrying screw threaded into a plug 47 carried by the side frame of the machine. This screw permits adjusting the amount of compression of the spring to determine the rate of trap door lift.

Lever 41 and its companion 42 are held in the position shown in Fig. 2 with the spring VS strongly compressed by interengagement between transverse pin 50 at the outer end of lever 41 and the closely fitting walls of the open ended slot 52 in the end of the short horizontal lever 53 mounted on stub-shaft 54 journaled in the side frame 30, as best seen in Fig. 4. On the outside of the frame a hand lever 58 is secured to shaft 54 by appropriate set screws 59 or other device. In normal operation the lever is horizontal, as shown in Fig. 5, and its free end is fitted with a transverse handle 60 having at its inner end a pin-like extension 61 slidable through a bore 62 in the enlarged end of the lever. Counterbore 63 receives a helical compression spring 64 bearing against a collar 65 on the part 61 to hold the handle drawn down with its shoulder 66 against the side of the lever. This projects the inner end 67 of the pin into a hole 68 in the side frame and the interlocking of these parts holds the lever in its normal position and maintains the bias on the spring VS in an obvious manner.

A second cross shaft 72 is journaled between the frames 30, 31 at approximately the level of rock shaft 43 but toward the direction of the cutter cylinder therefrom, and this shaft mounts a cam or eccentric 73 driven by

gears (not shown) in unison with the rest of the press mechanism, one revolution for each sheet cut. Loosely mounted for relative rotation on rock shaft 43 is hub 75 carrying, on a short lever 76, a stud 77 on which is mounted the non-friction bearing 78 and the cam follower roller 79, which bears on the periphery of the cam 73.

As seen in Figs. 1 and 2, the hub 75 has an arm 82 projecting therefrom radially and in the direction of hub 42' and terminated in a pad 83 for cooperation with complementary pad 84 carried by an arm 85 extending in the opposite direction from hub 42' so that the two pads confront. In pad 84 is secured a stud 86 which extends loosely through an enlarged hole 87 in pad 83 and supports the substantially horizontal spring HS of greater strength than spring VS and able to overcome it in spite of a difference in lever arms. This spring HS is adjustable in compression by a suitable nut and lock nut assembly 88.

When, in normal operation of the press, the pin on hand lever 58 is engaged in hole 68 in the frame, the lever 41 and the cross shaft 43 are held in the position shown in Fig. 2, maintaining the bias on spring VS and holding the trap door closed. Under these circumstances the spring HS is cyclically flexed by the movement of the assemblage of hub 75, lever 76, its cam follower 79, the arm 82 and its pad 83, whereby the cam follower continuously bears on the surface of the eccentric cam as the press is in operation. Movement of pad 83 is from substantial engagement with pad 84 to the maximum separation effected by the eccentricity of the cam.

If the operator desires to remove a single sheet for inspection, he pulls outwardly on handle 60, withdrawing pin end 67 from the hole 68 in the frame. The handle end of the lever will then be lifted under the action of spring VS as the cam follower rides the descending surface of the cam to its low point. As the follower begins to move in a direction away from the center of cam shaft 72 by following the rise of the cam, pad 83 is moved in a counterclockwise direction as viewed in Fig. 2 and the stud 86 and spring HS cause the pad 84 to move with it, carrying lever 41 in a counterclockwise direction, compressing lesser strength spring VS, lowering pin 50 and returning hand lever 58 to the horizontal position where its spring pressed pin will snap into the frame aperture 68 to lock the system at the end of one cycle.

Should it be desired to obtain more than a single sheet by means of the trap door route, the operator merely lifts the handle 60 and holds it up. If he desires, he may draw it slightly beyond the position it would assume when the cam low point engages the follower, and permits the pin on the handle to enter the second opening 90 in the frame. This will maintain the trap door open continuously but as soon as the handle is withdrawn to release the pin from hole 90 the lever drops at least to the dotted position shown at 91 and at the end of the cam stroke returns to and is locked in the normal position.

Thus the apparatus achieves both the accurate length cutting of the sheets and the possibility of semi-automatic delivery of one or more sample sheets without disrupting the cutting and stacking mechanism.

I claim:

1. Divertor mechanism for articles travelling over a surface at a uniform rate and spacing under the action of delivery means including in combination, a divertor gate; means mounting said gate for movement to either of two article guiding positions; means biasing said gate

toward one of said positions; means resisting said bias and holding the gate in the other of said positions; a cam timed to rotate once for each article passing said gate; a spring; means actuated by said cam to flex said spring; means connecting said spring to apply an overriding force in opposition to said bias once per revolution of said cam; and means to manually release said gate holding means.

2. Mechanism as defined in claim 1 in which said means resisting said bias comprises latched means to hold said gate in said other position; a cam follower; a pivoted lever acting to connect said spring to apply said force in opposition to said bias; and means connecting said spring to maintain said follower against said cam irrespective of the lever position.

3. The invention of claim 2 in which a link connects said lever to said gate remote from its mounting means; said bias acts on said lever to urge the gate toward said one position and the latched means holds the lever to position the gate in the other position; said spring being compressed by said lever to urge said cam follower against said cam at all times.

4. The invention of claim 3 in which a latch on the latched means cooperates with a first keeper to hold the gate in said other position, a second keeper for the latch for securing the latched means in a position to hold the gate in the biased position continuously, said second keeper being slightly beyond the reach of the latch when the latched means is moved automatically for one stroke by said cam.

5. The invention of claim 3 in which the said spring is of sufficient strength to overpower said bias whereby said cam acts through the follower, said spring, the lever and the lift link to return the gate to the other of said positions against said bias.

6. Divertor mechanism for articles travelling over a substantially horizontal surface at a uniform rate and spacing under the action of delivery means including in combination, a trap door normally closing an opening in said surface; means hinging said trap door adjacent an edge remote from the approaching articles; a lever pivoted on a fixed fulcrum; a link connecting said lever and trap door remote from its hinged edge, spring means biasing said lever toward trap door opening position; a second lever engaging the first; means to latch said second lever to hold the first lever in trap door closing position; a cam timed to rotate once for each article passing said trap door; a third lever pivoted coaxially with the first and having a follower for said cam; a spring between said first and third levers to maintain said follower against said cam only when the second lever is latched and means to manually release the latch of the second lever whereby the follower is maintained against the cam by the said spring means to thereby open the trap door once per cam revolution.
